VALVE

Filed July 7, 1930

Rudolf Michl
INVENTOR.
BY Max S. Oldmann
ATTORNEY

UNITED STATES PATENT OFFICE

RUDOLF MICHL, OF BRIDGEPORT, CONNECTICUT

VALVE

Application filed July 7, 1930. Serial No. 465,899.

The present invention relates to fluid flow control means.

One of the common methods of fluid flow control is by means of a needle valve where- in a pin member is movable into and out of engagement with a valve seat formed at an orifice. The fluid jet which emerges from the orifice is however tubular in form because of the fact that the flow must be between the valve seat and pin walls. It is frequently desirable to have a solid jet of fuel emerge from the orifice irrespective of the size of the latter and the production of means for obtaining this desired result is one of the objects of my present invention.

A further object of the present invention is the provision of novel controlling means for the orifice.

Still another object is to so arrange said novel controlling means as to have minimum wear on the closure portions thereof, thereby insuring longevity thereof.

Still a further object is the provision of novel means for unitary control of the said closure means.

And another object is the provision of a device which may readily be manufactured at low cost.

With the above and other objects in view my invention comprises the novel combination, arrangement and construction of elements to be hereinafter more fully described, shown and defined in the appended claims.

In the accompanying drawings in which similar reference characters denote corresponding parts:—

Fig. 1 is a sectional elevation of one form of my device mounted to a combustion engine and adapted to be used as a fuel inlet control;

Fig. 2 is a section along line 2—2 of Fig. 1; and

Fig. 3 is a vertical section of a modified structure showing unitary control means for the orifice closure elements.

Referring to the drawings, 10 may denote an engine of the Diesel or other injection type which has my controlling device or valve 11 suitably mounted in the fuel inlet opening 12 thereof.

My valve proper may comprise a suitably shaped block 13 provided with a longitudinal hole or fuel passageway 14. The said hole may be of uniform dimensions throughout and may have an orifice 15 at one end. Suitably arranged in said block and making equal angles with the longitudinal axis of said passageway 14 and diametrically opposite each other are journalling holes 16 and 17 respectively, the diameters of which are at least equal to the diameter of said orifice. The holes 16 and 17 lead into said passageway 14 directly opposite each other. The other ends of said holes 16 and 17 are provided with countersunk portions 16' and 17' for a purpose hereinafter to be specified.

Adapted to be slidably mounted in the journalling holes are orifice closure members which may comprise pins 18 and 19 which latter have only sufficient clearance in their respective holes to permit sliding therein. The inner ends of said pin members are beveled as at 18' and 19' so that when the pin members are in their innermost position, the respective beveled faces engage each other and at this time the passageway 14 is completely closed. Sliding of said pin members outwardly causes the bevelled face to spread apart and expose correspondingly more and more of the passageway. Suitable means for continuously urging said pin members into their outermost positions, as springs 20 in the countersunk portions of said journaling holes may be provided. To slide the pin members, bolts 21 threadedly adjustable and located near free ends of said countersunk holes may be provided. Each of said pin members may be individually adjusted by its respective bolt 21.

It will be noted that the exposure of the passageway is always from the center thereof outwardly and consequently irrespective of the amount of exposure, the fluid jet emerging from the orifice will always be solid.

It is desirable in most cases to have common means for controlling the two pin members in order that they may be moved simultaneously.

In Fig. 3 is shown one way of accomplishing this result. The structure in general is

essentially the same as that of the first modification except that the upper face of block 13' is provided with an annular groove 22 into which the heads 18^a and 19^a of said pins project. The said block is also provided externally with a threaded portion 23 and a cap-like member 24 having a threaded portion 25 adapted to screw thereon. The inner face of said cap member may be provided with an 10 annular rib member 26 which latter is adapted to ride in said groove 22 on said pin heads. Thus by screwing said cap member inwardly or outwardly corresponding simultaneous motion of said pin members is obtained, 15 thereby respectively closing or opening the passageway.

Suitable means for attaching either of the devices to an engine as for instance by the threaded ends 13^a on each of said blocks may 20 be employed. Likewise the free ends of said fuel passageways 14 may have a threaded countersunk portion 27 into which the fuel leads 28 may be screwed.

My device may be modified in many ways 25 and is not limited in its application to valves for engines, but may be used universally for fluid control purposes. Likewise it is not necessary that two pins only need be employed for orifice control as three or more 30 pins may also be employed provided the engaging ends thereof are correspondingly bevelled.

My invention may be modified in various 35 other ways without departing from the spirit thereof and I do not wish to be limited to the details shown and described.

What I claim is:—

1. A fluid control valve comprising a block 40 having a fluid passageway therethrough and means for producing a solid fluid jet of controlled size, said means comprising slideable plunger members shaped at their lower ends to engage each other, supported in journalling holes in said block and adapted to project into said passageway and close off the latter and means for moving said plunger members into and out of engagement with each other.

2. A fluid control valve comprising a block 50 having a fluid passageway therethrough and means for producing a solid fluid jet of controlled size, said means comprising slideable plunger members angularly arranged with respect to said passageway and shaped at 55 their inner ends to engage each other, supported in journalling holes in said block and adapted to project into said passageway and close off the latter and means for moving said plunger members into and out of engagement with each other.

3. A fluid control valve comprising a block 60 having a fluid passageway therethrough and means for producing a solid fluid jet of controlled size, said means comprising slideable plunger members having cross-sectional di-

mensions at least equal to the diameter of said passageway and shaped at their inner ends to engage each other, supported in journalling holes in said block and adapted to project into said passageway and close off the latter and means for moving said plunger members into and out of engagement with each other.

4. A fluid control valve comprising a block 70 with a fluid passageway therethrough, means for producing a solid fluid jet of controlled size, said means comprising slideable plunger members shaped at their inner ends to engage each other, supported in journalling holes in said block and adapted to project into said passageway and close off the latter, means continuously tending to urge said plungers apart and means for moving said plunger members into and out of engagement with each other.

5. A fluid control valve comprising a block 75 having a fluid passageway therethrough and means for producing a solid fluid jet therefrom of controlled size, said means comprising slideable plunger members angularly arranged with respect to said passageway and supported in journalling holes in said block, said plungers having a diameter at least equal to the diameter of said passageway 80 and shaped at their inner ends to engage each other and close off said passageway, means for continuously urging said plunger members out of engagement with each other and individual means for separately controlling each of said plungers.

6. A fluid control valve comprising a block 90 having a fluid passageway, and means for producing a solid fluid jet therefrom of controlled size, said means comprising slideable plunger members angularly arranged with respect to said passageway, said plungers being shaped at their inner ends to engage each other, supported in journalling holes in said block and adapted to project into said passageway and close off the latter, means 95 for continuously urging said plunger members out of engagement and means for simultaneously moving said plunger members into and out of engagement with each other.

7. In a device as per claim 6, in which said last named means includes a cap member provided with an annular rib adapted to bear against said plunger members and means for adjustably mounting said cap member to said block.

8. In a device as per claim 5, in which said last named means includes threaded bolt members adapted to engage said plunger members and move the latter when said bolt members are moved.

9. A fluid control valve comprising a block 100 having a fluid passageway and means for producing a solid fluid jet of controlled size, said means comprising slideable plunger members angularly mounted with respect to said

fuel passageway and supported in journalling holes in said block, said plunger members being bevelled at their inner ends to engage each other and close off said passageway, spring means at the outer ends of said plunger members to continuously urge the latter out of engagement with each other and adjustable means for moving said plunger members into engagement with each other.

10. A fluid control valve comprising a block having a fluid passageway therethrough and journalling holes in said block angularly arranged with respect to the longitudinal axis of said passageway and diametrically opposite each other, said holes being at least equal in diameter to that of said passageway, plunger members slidably mounted in said journalling holes, the inner ends of said plunger members being bevelled and adapted when said members are in said innermost position to engage each other and completely close said passageway, means for continuously urging each of said plunger members into its outermost position and means for moving said plunger members inwardly counter to said outwardly urging means.

11. A fluid control valve comprising a block having a fluid passageway therethrough and journalling holes in said block angularly arranged with respect to the longitudinal axis of said passageway and diametrically opposite each other, said holes being at least equal in diameter to that of said passageway, plunger members slidably mounted in said journalling holes, the inner ends of said members being bevelled and adapted when said members are in their innermost positions to engage each other and completely close said passageway, means for continuously urging each of said plunger members into its outermost position and means for simultaneously moving said plunger member inwardly counter to said outwardly urging means.

In testimony whereof I affix my signature.
RUDOLF MICHL.
